(No Model.)

J. MILLER.

GRINDING DEVICE FOR ROTARY CUTTERS.

No. 531,547.

Patented Dec. 25, 1894.

fig. 1

fig. 6

UNITED STATES PATENT OFFICE.

JOHN MILLER, OF NEWTON, NEW JERSEY, ASSIGNOR OF TWO-THIRDS TO
JOHN HUSTON AND IRA C. MOORE, OF SAME PLACE.

GRINDING DEVICE FOR ROTARY CUTTERS.

SPECIFICATION forming part of Letters Patent No. 531,547, dated December 25, 1894.

Application filed March 12, 1894. Serial No. 503,299. (No model.)

To all whom it may concern:

Be it known that I, JOHN MILLER, a citizen of the United States, residing at Newton, in the county of Sussex and State of New Jersey, have invented certain new and useful Improvements in Grinding Devices for Rotary Cutters; and I do hereby declare the following to be a full, clear, and exact description of the invention, such as will enable others skilled in the art to which it appertains to make and use the same.

My invention relates to improvements in grinding-devices for rotary-cutters or similar tools.

15 The invention will first be described in connection with the accompanying drawings, and then particularly pointed out in the claims.

In the drawings—Figure 1 is a plan view of a grinding device embodying my invention.

20 Fig. 2 is a front elevation of the same. Fig. 3 is a side elevation of the same. Fig. 4 is a vertical section through the center of the tool holder. Fig. 5 is a horizontal section showing the ratchet. Fig. 6 is a detail view of the sleeve.

25 Referring to the drawings, 1 is an ordinary arbor, journaled at 2 and provided with a pulley 3 by which it is revolved. On the end of the arbor is fixed an emery wheel 4 or similar grinding device. To the frame 5 which supports the journal boxes 2 is attached an arm 6, which is slotted at its outer end at 7. In this slot is secured a ratchet case 8 by means of a stud 9 fixed to the bottom of the ratchet-case, this stud 9 entering the slot 7 and being secured to the arm by a nut 10 and washer 11, the stud being thus held from movement in the slot when the nut 10 is tightened.

30 To the top of the ratchet case 8 is secured a cap 12 by means of screws 13, the cap having a central opening through which projects a tool arbor 14 fixed to a ratchet-wheel 15, the latter being located within the ratchet-case 8. The ratchet-teeth of the ratchet-wheel 15 are arranged to be engaged by a pawl or dog 16, which is movable in a recess in the ratchet-case and is fixed to a pawl-rod 17, the latter projecting outside the ratchet-case where it is provided with a milled head 18. The pawl 45 is held into engagement with the teeth on the

ratchet-wheel by means of a spring 19, which surrounds the pawl-rod 17, as will be plain from the drawings.

That portion of the tool-arbor which projects above the cap 12 is slotted, as at 20, and on this portion of the said arbor is mounted a sleeve 21 provided with a spline or feather 22 which enters the slot 20 in the tool-arbor, thus permitting the sleeve, 21, to move up and down on the arbor yet compelling the arbor to rotate when the sleeve is turned.

50 The sleeve has a squared portion 23, a cylindrical central portion 24, on which the tool to be ground is placed, and a screw-threaded end 25 onto which is screwed a nut 26, preferably milled on the edge, as shown.

55 The operation of my device is as follows: The rotary cutter to be sharpened is placed on the sleeve, as shown at 27, and the nut 26 screwed down so as to clamp the cutter against the shoulder formed by the top of the squared portion 23. While this is being done the sleeve is held at the upper end of the tool arbor, and as soon as the rotary cutter to be ground is fixed to the sleeve the emery wheel 70 75 is set in motion by power from any suitable source. The sleeve is then allowed to drop down gradually on the tool-arbor, the edge of the emery wheel entering the proper space between the bits of the cutter and grinding the side of the approximate bit. The sleeve is then raised with the cutter until the latter is clear of the emery-wheel, whereupon the sleeve and with it the arbor is rotated one tooth of the ratchet-wheel, which can be determined by the clicking of the pawl. The sleeve is rotated by means of the squared portion 23 which is grasped by the operator.

80 The number of teeth on the ratchet-wheel is equal to the number of bits or teeth on the cutter, and therefore when the tool arbor is rotated one tooth of the ratchet-wheel, the next tooth or bit of the cutter is brought into its proper position for contact with the revolving emery-wheel, whereupon the sleeve 85 is moved downward until the second tooth of the cutter is sharpened the operation being repeated as before until the whole cutter is sharpened. By means of the stud 9, slot 7 and nut 10 the tool-holder may be adjusted 90 95 100

with relation to the emery-wheel in order to compensate for the wearing of the emery-wheel.

Having thus fully described my invention, 5 what I claim as new, and desire to secure by Letters Patent, is—

1. In a rotary-tool grinding-device, the combination, with a slotted tool-arbor, a ratchet-wheel fixed thereon, and a spring-pawl in engagement with the ratchet-wheel, of a sleeve mounted on the tool-arbor and provided with a feather engaging the slot in the arbor, and a nut threaded onto the end of the sleeve, substantially as described.
- 15 2. In a rotary-tool grinding-device, the combination, with a grinding wheel, an arbor on which the wheel is fixed, means for revolving the arbor, a frame in which the arbor is jour-

naled, an arm attached to the frame and provided with a slot, a ratchet-case having a stud 20 adjustably secured in the slot, a ratchet-wheel located in the ratchet-case, a pawl, a spring normally holding the pawl into engagement with the ratchet, means for withdrawing and a sleeve arbor fixed to the 25 ratchet-wheel, of a sleeve movable on the tool-arbor and provided with a feather engaging the slot in the tool-arbor and a nut screwed onto the sleeve, substantially as described.

In testimony whereof I affix my signature in 30 presence of two witnesses.

JOHN MILLER.
